D. E. O'MALLEY.
AUTOMATIC AIR VALVE FOR GAS ENGINES.
APPLICATION FILED JAN. 15, 1920.

1,361,771.

Patented Dec. 7, 1920.

UNITED STATES PATENT OFFICE.

DANIEL E. O'MALLEY, OF SALINA, KANSAS.

AUTOMATIC AIR-VALVE FOR GAS-ENGINES.

1,361,771.

Specification of Letters Patent. Patented Dec. 7, 1920.

Application filed January 15, 1920. Serial No. 351,540.

To all whom it may concern:

Be it known that I, DANIEL E. O'MALLEY, a citizen of the United States, residing at Salina, in the county of Saline and State 5 of Kansas, have invented certain new and useful Improvements in Automatic Air-Valves for Gas-Engines; and I do declare the following to be a full, clear, and exact description of the invention, such as will 10 enable others skilled in the art to which it appertains to make and use the same.

This invention relates to improvements in automatic air valves for gas engines, and it has more particular reference to an air 15 valve which is especially designed to be used in connection with automobile engines.

The principal object of the invention is to provide an air valve of the above mentioned type which is designed to automatically 20 control the admittance of additional air into the intake manifold of an engine, the amount of air admitted being automatically varied and controlled according to the speed of the motor to which the air is being fed.

Another object of the invention is to provide an air valve of the above mentioned type which has manually controlled means incorporated therewith which is designed to 30 enable the valve to be retained in a position to supply a small quantity of air to the intake manifold when the engine is running at its lowest speed.

A further object of the invention is to 35 provide a device of the above mentioned character which is extremely simple in construction, yet highly effective in use, one which is automatic in operation, and is exceedingly inexpensive to both the manufacturer and the user, being of such construction that it may be readily applied on various types of automobiles and the like, by any unskilled person in the art.

Other objects and advantages of the invention will be apparent from the following description.

In the accompanying drawings forming part of this specification and in which like numerals are employed to designate like 50 parts through the same:

Figure 1 is a side elevation of a portion of an automobile engine equipped with my improved device.

Fig. 2 is an enlarged elevational view of 55 a device constructed in accordance with my invention.

Fig. 3 is a sectional view, partly in elevation, of the device.

Fig. 4 is a view taken on the plane of the line 4—4 of Fig. 3.

In the drawings, wherein for the purpose of illustration is shown a preferred embodiment of my invention, the letter A designates a portion of an automobile engine with which my device is associated. The 65 device is intended to supply additional air to the intake manifold of the engine (not shown), and it is so constructed that the amount of air supplied to the intake manifold will be controlled by means of a centrifugal governor 1 which is driven in any suitable manner. In this instance the governor is actuated by a belt 2 which is in turn driven by means of the fan shaft 3. While I have shown a belt-drive, I desire 75 to be understood that the governor may be actuated in any other manner, such as for instance, by suitable gearing.

My improved device consists of a suitable supporting member 4 which may be of any 80 construction, according to the type of engine to which it is secured. The engine shown is a Ford, and I have especially designed the support to be connected to a part of this engine in the manner shown. The 85 support shown includes a base 5 which is adapted to be secured by means of bolts to the usual flanges which serve to connect the engine block to the crank case. Rising from the base 5 are a pair of standards 90 6 and 7, and each of these standards is provided at its upper or free end with a bearing 8 or 9. Journaled in the bearing 8 is a shaft 10 which is driven by means of a belt 2, and mounted on this shaft in any suitable manner is the already referred to 95 governor 1. Secured in any suitable manner in the bearing 9, is a cylindrical piece of pipe 11 which will hereinafter be referred to, in conjunction with the tube 12, as the 100 air conduit. As is obvious, the tube 12 is adapted to lead to the intake manifold, being connected thereto in any desired manner. Slidably mounted within the air conduit is a cylindrical valve 13, which has 105 swivel connection with the centrifugal governor mechanism. This valve 13 is provided with oppositely disposed substantially V-shaped slots 14 which are designed to be uncovered by slidable movement of the valve, such movement being controlled by 110 the centrifugal governor. In order to limit

the outward movement of the valve 13, and also in order to prevent rotation thereof, I provide the pipe 11 with a laterally extending lug 15 which extends through one of 5 the slots 14.

With the foregoing construction, it will be seen that when the engine is running at a fast speed the centrifugal governor, which is controlled by the speed of the engine, will move to a position substantially as shown in Fig. 3. By reference to this figure it will be seen that the valve 13 has been moved to a position to uncover the slots 14, so, by means of the suction created with- 10 in the intake manifold, additional air will be drawn through the slots 14 and fed to the engine. Now, should the speed of the engine decrease, the valve will move to a closed position as is obvious, and air will be 15 excluded, that is, if the engine is running 20 at a very low rate of speed.

Inasmuch as it is not always desired to have the valve closed, even when the engine is running at a greatly reduced speed, 25 I have found it advantageous to employ means to retain the valve in a position to admit a small quantity of air. In carrying out this feature, I pivot a lever 16 on an ear formed on the bearing 9, and to one end of 30 this lever I connect a rod 17 which extends back toward the operator, and terminates within his reach so that it may be actuated by him. From this construction it will be seen that when the operator moves the rod 35 17 forward, the lever 16 will assume a position such as indicated in dotted lines in Fig. 3, in which position the lower free end thereof has been moved into the upper slot 14 in valve 13. So, it will be seen that this 40 position of the lever will prevent the valve from closing entirely. In other words, the valve 13 will not be permitted to move to its innermost position, therefore, the slots 14 will be partially uncovered and a small 45 quantity of air will be permitted to pass therethrough.

Attention is directed to the fact that the pivoted lever 16 also serves another purpose, that is, it may be used to hold the valve in 50 a closed position. This feature will be found advantageous when starting the engine, because it will prevent the admittance of the additional air which is not desired during the starting of the engine. To accomplish this feature the rod 17 will be moved forward by the operator, thus moving the free end of the lever 16 between the valve 13 and the centrifugal governor as indicated in dotted lines in Fig. 2, which position of parts will prevent opening of this 55 valve.

In the foregoing description and in the drawings, I have shown a particular type of supporting member 4, but I desire it to 60 be understood that this supporting member

may be of various other designs according to the type of automobile with which the device is to be used. The centrifugal governor too, may be associated with the valve in various other ways besides the way it is 70 shown in the drawings. The only essential part of my device, is a suitable supporting member, a valve of the type set forth, a conduit of the type described, and the means described, for limiting the inward and outward movement of the valve with respect to the conduit. 75

From the foregoing description taken in conjunction with the accompanying drawings, the manner in which my device operates is thought to be obvious; therefore, further description is deemed unnecessary. 80

It is to be understood that the form of my invention herein shown and described is to be taken as a preferred form of the 85 same, and that various changes in the shape, size, and arrangement of parts may be resorted to without departure from the spirit of the invention or the scope of the subjoined claims. 90

I claim:

1. An auxiliary air intake valve for internal combustion engines comprising a supporting member, an air conduit carried thereby, a valve sleeve slidable in said passage, a centrifugal governor connected to said sleeve, the latter being provided with a shoulder, and a manually controlled lever pivoted on the supporting member in a position to have its free end engaged behind 95 said shoulder and hold the valve closed. 100

2. An auxiliary air valve for internal combustion engines comprising an air conduit adapted to lead to the intake manifold, a centrifugally controlled valve slidably mounted in said conduit and provided with an opening adapted to be uncovered by its sliding movement, a supporting member for the foregoing parts, and a manually controlled lever pivotally mounted on the 105 member in a position to have its free end swung into the opening in the valve to retain the same in a partially uncovered position, also serving to hold the valve closed. 110

3. An auxiliary air valve for internal 115 combustion engines comprising an air conduit adapted to lead to the intake manifold, a centrifugally controlled valve slidably mounted in said conduit and provided with an opening adapted to be uncovered 120 by its sliding movement, a supporting member for the foregoing parts, and a manually operated member carried by the supporting member, being adapted to coact with the opening in the valve for retaining the latter 125 partially open.

4. An auxiliary air valve for internal combustion engines comprising a supporting member, a cylindrical air conduit carried by said member and adapted to supply 130

air to the intake manifold, a centrifugally controlled cylindrical valve slidable in said conduit and provided with oppositely disposed slots through which air is admitted, 5 said conduit being provided with a lateral projection which extends into one of said slots in the valve and serves to limit the outward movement of the latter and also prevents rotary movement thereof, and a

manually controlled lever pivotally mounted 10 on the supporting member in a position to have its free end swung into engagement with the valve to hold said slots partially uncovered, and also to hold the valve closed.

In testimony whereof I have hereunto set 15 my hand.

DANIEL E. O'MALLEY.
